TOY GUN

Filed Feb. 5, 1930

INVENTOR

Arthur Stanley Norbury

W. J. Haskett
his ATTORNEY

UNITED STATES PATENT OFFICE

ARTHUR STANLEY NORBURY, OF WINDSOR, ONTARIO, CANADA

TOY GUN

Application filed February 5, 1930, Serial No. 426,123, and in Canada February 7, 1929.

This invention relates to improvements in a toy gun and appertains particularly to a device of this character capable of throwing a projectile that is quiet and harmless.

5 An object of the invention is to provide a toy gun in which an elastic band serves the dual function of the propelling power and projectile.

10 A further object of the invention is to provide a toy gun adapted to project an elastic band and which is accordingly capable of affording children much pleasure in playing "cowboys and Indians", "war" and other games with the maximum of safety and without even the disturbance incidental to the use of cap-pistols.

15 A still further object of this present invention is the provision of a toy gun of the nature described, adapted to throw a rubber band projectile, that is characterized by structural simplicity, durability, and efficiency, capable of shooting relatively far and straight and of production at a reasonable cost whereby the same is rendered commercially desirable.

20 To the accomplishment of these and related objects as will become apparent as the description proceeds, my invention resides in the construction, combination and arrangement of parts as shall be hereinafter more fully described, illustrated in the accompanying drawings, and pointed out in the claim hereunto appended.

25 The invention will be best understood and can be more clearly described, when reference is had to the drawings forming a part of this disclosure, wherein like characters indicate like parts throughout the several views.

30 In the drawings:—

35 Figure 1 is a side elevation of a possible embodiment of my invention; and

Figure 2 is a plan view thereof.

40 My toy gun intended particularly for shooting elastic bands simulates a pistol to a marked degree though constructed very simply and cheaply. The barrel 5 is a length of dowel to the under rear portion of which the stock 6 is rigidly fastened. This stock 45 6, from the back of the barrel 5 depends to form the forward half 7 of the handle, whose

second or back half 8 hinges or pivots centrally on the forward half; a clothes pin spring 9 having a central coil part 10 as pivot and radially extending ends 11 terminally inturned serves to unit the two component parts of the handle and normally holds the upper end of the back half 8 of the handle, which is shaped to immitate a hammer 12, in spring urged engagement with the rear of the barrel 5.

45 The lower ends of the handle members 7 and 8 are normally spaced but can be pressed together against the action of the spring 9 so that the hammer-shaped upper end 12 of the back handle member 8 pivoting on the coil body of the spring 9 moves away from and out of engagement with the back of the barrel 5. The whole is completed and given a close resemblance to the ordinary pistol by inserting a small sighter in the forward end of the barrel and finishing the toy 50 with a coat of aluminum or other metallic paint.

55 As the preceding explanation is a clear concise description of the construction in detail of one embodiment of my invention so that anyone skilled in the art to which it applies will readily understand the same, it should now suffice in conclusion to make but brief reference to its use and modus operandi:—An elastic band of suitable length of either the manufactured variety or, for economy's sake, one cut from an old automobile tube has its ends overlapped and inserted 60

65 between the hammer end 12 of the back handle member 8 and the back of the barrel 5 and there frictionally held against accidental displacement and the central portion of the band is stretched over the front end of the barrel 5, then when it is desired to release the elastic projectile, the handle members 7 and 8 are squeezed together at the bottom, releasing the hammer end 12 from the clamping engagement with the back overlapped ends of the elastic band which thus freed flies forward. The projectile is harmless even at close range, easily recovered for repeated use and moreover the entire operation of the toy is quiet.

70 From the foregoing description taken in 100

connection with the accompanying drawings, it will be manifest that a toy gun is provided that will fulfill all the necessary requirements of such a device, but as many changes could be made in the above description and many apparently widely different embodiments of my invention may be constructed within the scope of the appended claim, without departing from the spirit or scope thereof, it is intended that all matters contained in the said accompanying specification and drawings, shall be interpreted as illustrative and not in a limited sense.

Having thus described my invention, what I claim as new and desire to secure by Letters Patent is:—

In a toy gun adapted to shoot elastic bands; a solid elongated barrel; a stock rigidly fastened to the underside of said barrel at the rear thereof and having an angularly depending rear end; an angular complimentary member operating on the angularly extended depending rear end of said stock and having its upper end provided with an angularly cut flat face opposed to the rear end of the barrel and serving to co-operate therewith to normally hold against the rear end of the barrel the overlapped ends of an elastic stretched over the outer end of said barrel, along the sides thereof and over the rear end of said barrel; and a fulcrum spring connecting said complimentary member with said angularly extended depending rear end of the stock at the connection of the angular portions of said complimentary member and said stock end.

In testimony whereof I hereunto affix my signature.

ARTHUR STANLEY NORBURY. [L. S.]
